[57] CLAIM

The ornamental design for a food processor tool holder, as shown and described.

DESCRIPTION

FIG. 1 is a top, front, and left side perspective view of a first embodiment of a food processor tool holder showing my new design;

FIG. 2 is a bottom, rear, and right side perspective view thereof;

FIG. 3 is a top plan view thereof;

FIG. 4 is a front elevational view thereof;

FIG. 5 is a right side elevational view thereof, the side opposite being a mirror image thereof;

FIG. 6 is a view similar to FIG. 1 but of a second embodiment of my food processor tool holder, the other views being similar to said first embodiment;

FIG. 7 is a view similar to FIG. 1 but of a third embodiment of my food processor tool holder, the other views being similar to said first embodiment;

FIG. 8 is a view similar to FIG. 1 but of a fourth embodiment of my food processor tool holder;

FIG. 9 is a bottom, rear and right side perspective view of FIG. 8;

FIG. 10 is a top plan view of FIG. 8;

FIG. 11 is a front elevational view of FIG. 8;

FIG. 12 is a right side elevational view of FIG. 8; and

FIG. 13 is a view similar to FIGS. 1 and 8 but of a fifth embodiment of my food processor tool holder, the other views being similar to said first and fourth embodiments.
